Primary Examiner — Patricia A Palasik*(74) Attorney, Agent, or Firm* — Westerman, Hattori, Daniels & Adrian, LLP(57) **CLAIM**

The ornamental design for a robot arm apparatus, as shown and described.

DESCRIPTION

FIG. 1 is a perspective elevational view from a top-front-right direction of a first embodiment;

FIG. 2 is a perspective elevational view from a top-rear-left direction of the first embodiment;

FIG. 3 is a front elevational view of the first embodiment;

FIG. 4 is a rear elevational view of the first embodiment;

FIG. 5 is a top plan elevational view of the first embodiment;

FIG. 6 is a bottom elevational view of the first embodiment;

FIG. 7 is a right side elevational view of the first embodiment; and,

FIG. 8 is a left side elevational view of the first embodiment.
